UNITED STATES PATENT OFFICE.

CHARLES EDWARD HOPKINS, OF PLAINFIELD, NEW JERSEY.

STEREOTYPE-FINISHING APPARATUS.

1,354,751.

Specification of Letters Patent.

Patented Oct. 5, 1920.

Original application filed April 26, 1909, Serial No. 492,103. Divided and this application filed November 12, 1915, Serial No. 61,025. Renewed May 21, 1919. Serial No. 298,789.

To all whom it may concern:

Be it known that I, CHARLES E. HOPKINS, a citizen of the United States, residing at Plainfield, county of Union, State of New Jersey, have invented a new and useful Stereotype-Finishing Apparatus, of which the following is a specification.

This is a division of my patent on stereotype apparatus, No. 1,160,985 patented November 16, 1915, on an application filed April 26, 1909, Serial No. 492,103.

The object of the invention is to provide a machine for finishing curved stereotype plates in a minimum of time and with a minimum of labor. The improvements have been devised largely with the idea of providing an apparatus which may be operated at a considerable speed by one man to trim, shave and cool the stereotype plates so that they may be quickly finished and made available at once for attachment to the ordinary newspaper web perfecting printing presses.

The apparatus shown in the accompanying drawings is an embodiment of the invention which has been designed particularly for use in printing plants of second class newspapers where the saving of labor is important and where economy of time is necessary. This apparatus, also, is adapted to be operated in conjunction with any melting pot and pump and that may already be installed on the premises. Referring to this machine and to the accompanying drawings,

Figure 1 is a plan view of the machine; Fig. 2 is a view in side elevation with the speed reducing gearing in section;

Fig. 3 is a view in central longitudinal section;

Fig. 4 is a plan view of a portion of the finishing mechanism;

Fig. 5 is a view partly in section and partly in elevation, of the finishing and cooling mechanism;

Fig. 6 is a sectional detail view of the finishing mechanism on a plane indicated by the line 6-6 of Fig. 3;

Fig. 7 is also a detail sectional view showing a portion of a full sized stereotype plate being trimmed and a portion of the holding means;

Fig. 8 is a detail view in elevation showing a stereotype positioned upon the half-cylinder support or horse of the finishing mechanism;

Fig. 9 is a similar view after the horse has 55 made a one-half revolution;

Fig. 10 is a similar view after the horse has completed one revolution;

Fig. 11 is a similar view showing the horse after it has made a revolution and a half; 60

Fig. 12 is a view showing the horse in section and the trimming mechanism taken upon a plane indicated by the line 12-12 in Fig. 3, and

Fig. 13 is also a detail view of a section 65 taken partly on the plane indicated by the line 13-13 in Fig. 3, and also showing the starting lever and holding means 96 and 97.

In the present machine, the back 10 is supported in an upright position at the rear end 70 of the frame 11 to which it is securely fixed. Directly in front of the concave side of the back is the core 12 which is supported upon rockers 13 movable back and forth upon tracks 14 provided in the frame, and for the 75 purpose of rocking said core from a horizontal position to a vertical position and back again, a handle 15 is secured to the core at one side thereof and near what may be referred to as the top end of the core. The 80 object of thus rocking the core is to form with the back a chamber in which a curved stereotype plate may be cast from a matrix held in said chamber and which core with the plate and matrix may be withdrawn 85 from the back and be moved from a vertical to horizontal position.

Movable upon studs fixed along each of the straight sides of the core are straight bars or lifters 30 which assist in forming 90 the straight side walls or closures of the casting chamber. Coöperating with the side bars 30 are members 31 mounted upon the ends of a cross-shaft 20 which passes through the cross-brace 19. These members 31 can turn 95 on the shaft sufficiently to engage the under side edges of the side bars 30 when the core is rocked about midway between its two limiting positions. The shaft 20 and members 31 occupy such a position relative to the 100 track 14, rockers 13 and side bars 30 that upon the turning of the core away from the back to its horizontal position the members 31 engage the side bars about midway of the movement, and during the latter part of the turning movement the side bars 30 in engagement with the members 31 will be caused to move relatively to the core. This

motion is sufficient to separate the stereotype plate and matrix from the core so as to cause it to be supported above the same by the bars or members 31 and free it from the 5 core. On the member 31 is a stop-pin 32 and fixed to the shaft 20 is a stop-pin 33. During the motion of the member 31 these come into contact so as to limit the movement of this member. Near the top of the 10 core and pivoted to one of the side bars 30 is a small flexible band or tail piece 37. The free end of this is provided with a catch hook 38 and a handle for moving the band on and off the core. The other side bar 30 15 is provided with a spring-actuated catch 39 which is adapted to be engaged by the hook 38 when the band is positioned over the core. This band prevents the molten metal running behind the matrix during casting.

20 After the casting and the withdrawal of the core from the back, the plate is left raised slightly above the core in the position shown in Fig. 3. After the matrix has been stripped from the plate in this position and 25 the plate has been released by the unfastening of the tail piece or band 37, it is slid longitudinally by the operator upon a support or horse 73, which is in alignment with the core while the latter is in its horizontal 30 position. The plate is positioned upon the horse by having a lug 69 cast therein which, when the plate has reached its proper position upon the horse, abuts against an adjustable stop 94. This is adjusted by a head 35 65 on the screw on which the stop is mounted. The horse is semi-cylindrical in shape and is rotatable about a shaft 72, the rotation of the horse being adapted to transfer the plate therefrom to a stationary concave 40 bed 71 directly underneath the horse and of a length equal to the type face of the stereotype. While in this bed, the stereotype is 45 finished by being trimmed and shaved.

For the purpose of transferring the stereotype from the horse to the bed, Figs. 50 8 to 11, one edge of the horse is provided with movable fingers 76 which when closed are flush with the cylindrical face of the horse but when in operation protrude sufficiently to engage the edge of the stereotype 55 thereupon. In this way, when a stereotype is placed upon a horse and the horse is revolved, the fingers during the first half revolution of the horse are kept in engagement with the plate by a spring but at the end of the first half revolution the fingers 76 are withdrawn against the action of the spring by means of a cam 81. At the same time that the fingers are withdrawn, or substantially the same time, a spring operated stop 83 along one edge of the bed is allowed 60 to move into operative position by a cam 82 and thus serves to check the further rotation of the stereotype plate which by this 65 time is resting upon the bed; the horse, how-

ever, continuing upon its second half revolution. During this second half revolution of the horse and while the plate is resting upon the bed the plate is shaved and trimmed by a knife 74 and a saw 84 respectively. The 70 knife 74, which is of a length equal to the finished plate, is positioned so as to engage and slide upon the ribs of the plate, being secured to the shaft 72 of the horse. A brush 75 also secured to the same shaft, 75 follows the knife and brushes out the interior of the stereotype after it has been shaved. The saw 84 is carried upon one end of a shaft 86 journaled in a segmental extension 85 of the horse and is driven at high 80 speed through sprockets 87 and 88 which are connected by a sprocket chain and the latter of which is a double sprocket and is mounted freely upon the shaft 72 so as to be driven from a sprocket 89 fast to the 85 driving shaft. It will thus be seen that the saw 84, is driven independently of the horse but moves with the horse so as to cut off the riser portion of the plate. From Figs. 9 and 10 it will be seen that the plate is 90 trimmed during the second half revolution of the horse and that during this half revolution the extension 85, (Figs. 2, 3 and 8) which is about a quadrant in width, forms a support for the riser portion of the stereotype 95 as it is being separated from the type face portion of the plate and thus prevents the severed portion from twisting or bending the plate on account of its unsupported weight. From Fig. 11 it will be seen that 100 upon the commencement of the fourth half revolution of the horse, the fingers 76 upon one edge of the horse will again be caused to protrude through the action of a spring under the control of the cam 81 and will engage one of the straight edges of the stereotype plate, and that simultaneously the stop 83 along one edge of the bed will be moved back out of the path of the plate through the cam 82. The continued rotation of the 110 horse therefore will now remove the plate from the bed and at the end of the second complete revolution of the horse the plate will again rest upon the horse and the latter will be in the position from which it started 115 where it will be checked through the operation of a clutch presently to be explained. It should be noted that while the plate is resting in the bed and is being operated upon by the shaving knife and trimming 120 saw, the edge 91 of a flat plate 90 which serves as a holding means (Fig. 7) moves in a groove formed between two ribs 68 cast in the concave side of the stereotype by grooves 70 (Fig. 3) in the core, such plate being held 125 in the groove by springs. In this way the plate is maintained in the proper position during the finishing and is also held firmly down upon the bed.

The cams 81 and 82 are fixed to a gear 78 130

(Fig. 3) which is freely mounted upon the shaft 72 and is in mesh with a gear 80 fast to a gear 79 which latter gear is in mesh with a gear 77 fast to the shaft 72. This arrangement is such that the cams 81 and 82 will revolve but once during two revolutions of the horse.

The shaft 72 is driven from the main driving shaft of the apparatus through the interposition of reduction gearing whereby a reduced speed is obtained for the horse without the loss of power which accompanies the use of worm gearing which is ordinarily provided for this purpose. This reduction gearing (Fig. 3) comprises a gear 101 operating loosely upon the shaft 72, a gear 108 coaxial therewith but fixed from rotation, as by being secured to the casing of the gearing, and a pinion 106—107 divided as shown so as to mesh with both gears and be carried by a crank arm 105 secured to a short shaft 104 journaled in one end of the shaft 72 and in the gear casing. This short shaft 104 is driven by a sprocket 103 connecting with the driving shaft 102 of the machine and causes the crank arm to revolve and carry the pinion 106—107 around the gears 101 and 108. As one of these gears 108 has a larger number of teeth than the other gear 101, each revolution of the crank arm 105 will cause the gear 101 to be advanced by as many teeth as are represented by the difference between the number of teeth between the gear 108 and the gear 101. In this way, it will be seen that the speed of the gear 101 can be made as slow as desired.

The gear 101 is made to drive the horse 73 and its shaft 72 through the interposition of a clutch which is shown clearest in Fig. 13. In this figure the shaft 72 will be seen to be provided with an arm 100 which is fast to said shaft and which has pivoted thereto a clutch pawl 99 adapted to engage with one of a series of notches cut into the interior face of the rim of the gear 101. Normally the pawl 99 is lifted by one arm of a clutch lever 98 so that the gear 101 revolves freely without moving the shaft 72. When however the operator has moved a stereotype plate on the horse and is ready to start the finishing device in operation, he lifts the handle 95 of the starting lever and thereby disengages the end of the pawl 99 from the arm 98 of the starting lever and permits said pawl to engage in one of the notches in the rim of the gear 101. This starts the horse rotating and the finishing devices in operation. The starting lever is provided with a hook 96 which, while the finishing devices are in operation, rides upon the face of a cam 97. This cam is secured to a gear which meshes with the gear 80 and is rotated once for every two revolutions of the horse. It is also provided

with a notch which the hook 96 is adapted to engage, and when in the revolution of the cam 97, the hook 96 drops into the notch, it permits the starting lever to return to its first position and the arm 98 to check the movement of the pawl 99 by moving in the path thereof and thereby cause a disengagement from the notch in the gear 101 with which it is in engagement. The hook 96 also serves as a means for locking the cam 97 which has a geared connection to the horse and thereby locks or holds the horse in the desired position. Thus, as is obvious, the further revolution of the horse will be checked, and it will be seen that due to the mechanism just described the horse will turn through two complete revolutions each time the clutch is operated by the starting lever 95.

After the plate has been operated upon by the finishing means and the horse has returned to its first position with the plate thereon, it is then lifted by manually operated transfer means from the horse and deposited on a semi-cylindrical support 121 constituting a part of the cooling means. This transfer means includes two uprights 109 and 110 at one side of the horse 73, and between these uprights there is pivoted a carrying frame 111 operated by a lever 112 having depending spring fingers 114 provided with beveled ends 115 and notches 116 near said ends. These fingers are pivoted upon a shaft 113 where they are slidable along the shaft under the action of their springs and said shaft is provided with a crank arm 117 which is connected by a link 119 with an extension 118 upon the upright 110, the object of which is to keep the arms 114 always vertical as the frame swings from one side of the uprights to the other. The horse is provided with recesses 120 into which the beveled ends of the arms 114 can enter so that after the stereotype has been finished, the operator, by turning the operating lever 112 may force the bevels of the arms 114 down over the bevel of the finished stereotype and into the recesses 120 of the horse. This causes the arms to separate against the action of their springs and a further movement pushes the arms down far enough to cause the notches 116 to engage upon the ends of the stereotype. Then the operator reverses the movement of the transfer lever 112 thus lifting the stereotype from the horse and deposits it upon the support 121 of the cooling mechanism which is located beside the horse. This support is slightly longer than the stereotype and therefore when the stereotype is lowered upon this support the bevels of the arms 114 engage the ends of the support and cause the arms to be forced outwardly against the action of their springs and the plate to be disengaged from the notches 130

116 after which the frame 111 is raised through the action of its counterbalance spring 126 attached to one end of an arm 127. A valve 122 of the cooling mechanism 5 is depressed by the plate, upon the latter being deposited upon the support 121, and permits water to flow from the supply pipe 123 into a distributing chamber at the end of the cylinder having an elongated opening 124, from which chamber it flows up through a groove against the stereotype plate, flushing and cooling the same, the water thereafter being carried away by a pipe 125 which leads from a trough for the 10 cooling water located underneath the support 121.

After the plate has been cast the operator grasps the handle 15 and rocks the core forward up into the position shown in Fig. 20 2 with the plate and matrix thereon. During this turning movement of the core the plate lifters 30 engage the members 31, which forces the lifters 30 to rise over the straight edges of the core and push the 25 stereotype plate free from its periphery, as shown in Fig. 3. The tail piece 37 is then loosened by hand and swung up to one side, as shown in Figs. 1 and 2. The plate is then moved by hand over on the horse 73 30 until the projection 69, moving along a slot 64, comes into contact with the adjustable stop 94 which positions the plate properly on the horse. The operator now lifts the handle 95 and thereby disengages 35 the end of the pawl 99 from the arm 98 of the starting lever which permits the pawl to engage in one of the notches of the gear 101. This starts the horse rotating and starts the finishing operation. The parts 40 start to rotate in the position shown in Fig. 8 and move in the direction of the arrow so that the cam 82 immediately allows the stop 83 to move into the position shown in Fig. 9, the spring actuating it in this 45 direction. At this time the fingers 76 are located under the following edge of the plate so as to carry the plate around with the horse. When the plate moves around to the position shown in Fig. 9, the cam 81 50 comes into operation to release the fingers 76 from the plate and leave the plate in the bed 71 with its forward edge up against the stop 83. The right angled extension of the slot 64 is provided to allow the projection 69 to pass out. A half rotation of the horse is now completed and it now starts on the second half rotation when the fingers 76 are kept retracted by the cam 81. It 55 will be seen therefore that the first half rotation is for placing the plate in the bed while the second half rotation is for the purpose of finishing the plate, which is accomplished by the operation of the knife 74 on the internal ribs and the planetary saw 84 trimming off the edge. The brush 75 moving

with the shaft follows the knife 74 and brushes out the interior of the plate after it has been shaved. During the cutting of the tail off by means of the saw 84 the extension 85 supports the tail or riser. At 70 the commencement of the fourth half revolution of the horse the fingers 76 again protrude controlled by the cam 81 but operated by the spring and the stop 83 is withdrawn. Continued rotation of the horse 75 thereafter moves the plate from the bed and at the end of the second complete revolution the plate is left on the horse in its initial position. The rotation of the horse is stopped at this point by the hook 96 coming 80 around at this time into a notch in the cam 97 which actuates the lever 95 and allows the pawl 99 to be disconnected from its ratchet wheel 101, and also locks the parts in this 85 position.

The plate having been operated upon to be finished and cleaned out as stated, it is lifted by the manually operating transfer means controlled by the handle 112 and swung over to the position shown in full 90 lines in Fig. 5 and through this position into contact with the support 121. This time it engages the valve stem 122 and opens the valve to turn on the cooling water. 95

Although I have illustrated and described a preferred embodiment of the invention, I am aware of the fact that many modifications can be made therein by any person skilled in the art without departing from 100 the scope of the invention as expressed in the claims.

Therefore, I do not wish to be limited to all the details of construction herein shown and described, but what I do claim is: 105

1. In a stereotype finishing apparatus, the combination of means adapted to deliver the plate in a horizontal position, a horse to support the plate in alinement therewith, means to position said plate on the horse, 110 and means in operative relation with the horse for finishing the plate.

2. In a stereotype finishing apparatus, the combination of means adapted to deliver the plate in a horizontal position, a horse to support the plate in alinement therewith, means for performing finishing operations 115 on the plate while on the horse, and a bed underneath the horse.

3. In a stereotype finishing apparatus, the combination of means adapted to deliver the plate in a horizontal position, a horse to support the plate in alinement therewith, means to position said plate on the horse, and a bed underneath the horse upon which 125 the plate may be deposited from the horse for finishing.

4. In a stereotype finishing apparatus, the combination of a horse to support the plate, means to rotate the horse, a bed underneath 130

- the horse, means along one edge of the horse to engage the edge of the plate, means along one edge of the bed to check the plate, and means to withdraw the first named means 5 from operation and throw the second named means into operation when the plate has reached its proper position upon the bed.
5. In a stereotype finishing apparatus, the combination of a rotatable horse to hold the 10 plate, a bed underneath the horse, finishing means for the plate, and means operating to deliver the plate from the horse to the bed during the first half revolution of the horse, means to bring the finishing means into operation 15 during the second half revolution of the horse, and means to deliver the plate again upon the horse during the second complete revolution of the horse.
6. In a stereotype finishing apparatus, the 20 combination of a rotatable horse, a stationary bed beneath the horse, finishing mechanism mounted to revolve with the horse, means operating with the horse to deliver the plate from the horse to the bed, finish 25 the plate and deliver it upon the horse again during two revolutions of the horse, and means to check the horse after it has made two revolutions.
7. In a stereotype apparatus for finishing 30 a plate with a groove therein, the combination of a bed in which the plate is finished and a revolving member adapted to travel in said groove to hold the plate in position while it is being finished.
- 35 8. In an apparatus for finishing a plate with a groove therein, the combination of a bed, a rotating horse to deliver the plate to and from said bed, and a member adapted to revolve with said horse and to travel in 40 said groove to hold the plate in position.
9. In a stereotype apparatus, the combination with means for cutting off the riser portion of the plate, and a movable support for the riser portion during the cutting.
- 45 10. In a stereotype apparatus, the combination of a bed to hold the plate during the finishing, a cutter movable across the plate to sever the riser portion thereof, and a support for the riser portion movable with the 50 cutter.
11. In a stereotype apparatus, the combination of a bed to hold the plate during finishing, a rotatable horse to deliver the plate to and from the bed, a segment projecting 55 from one end of the horse and forming a support for the riser portion of the plate during finishing, and a cutter carried by the segment to sever the riser portion.
- 60 12. In a stereotype apparatus, the combination of a rotatable horse to receive the plate, a shaft for the horse, reduction gearing on one end of the shaft, a cam on the other end of the shaft, a bed for the plate underneath the horse, and operative connec- tions between the horse and cam whereby 65 the plate may be delivered to and from the bed by the horse.
13. In a stereotype apparatus, the combination with a bed for receiving a plate, of a shaving knife rotatable above the bed, 70 and a rotating brush for cleaning out the plate.
14. In a stereotype apparatus, the combination with a bed for receiving a plate, of a shaving knife rotatable above the bed, 75 a brush rotatable in the rear of the shaving knife to sweep out the plate, and means to introduce a plate into the bed.
15. In a stereotype apparatus, the combination of a rotatable horse to hold the 80 plate after casting, of a bed underneath the horse to receive the plate for finishing, finishing means for the plate, means for brushing the plate, and means to deliver the plate from the horse to the bed. 85
16. In a device of the character described, the combination with a finishing means comprising a horse for supporting the plate, of a manually operated mechanism for engaging the top end edges of the plate and 90 moving the plate to one side of the horse.
17. In a device of the character described, the combination with a finishing means comprising a horse for supporting the plate, of a swinging frame having depending 95 spring fingers for engaging the plate, and a crank arm for keeping said fingers in vertical position, whereby the plate can be moved from the horse.
18. In a stereotype apparatus, the combination of a horse to support a finished plate, cooling means beside the horse, a swinging frame having depending spring fingers, the horse having means into which 100 said fingers may be inserted to lift the plate by its ends, and the cooling means having a support for the plate slightly longer than the plate in order to separate the fingers and release the plate when it has been delivered thereto. 105
19. In a stereotype apparatus, the combination with means to hold a plate stationary while shaving the back, and means to shave the back, of means for cleaning out the plate in a dry condition. 110
20. In a stereotype apparatus, the combination of a horse to support a finished plate, a swinging frame having depending spring fingers, the horse having means into which 115 said fingers may be inserted to lift the plate by its ends, and a support for the plate slightly longer than the plate in order to separate the fingers and release the plate when it has been delivered thereto. 120
21. In a stereotype apparatus, the combination with cooling means for the plate, of a manually operated frame for transferring a plate to the cooling means. 125

22. In a stereotype apparatus, the combination with cooling means for the plate, of a swinging frame having depending spring fingers adapted to engage the ends of the plate.

23. In a stereotype apparatus, the combination with cooling means for the plate,

of a swinging frame having depending spring fingers and a crank arm to keep said fingers in a vertical position.

10

In testimony whereof I have hereunto set my hand.

CHARLES EDWARD HOPKINS.
